DESIGN FOR A COAT

Mario Frascino, New York, N. Y.

Application December 19, 1940, Serial No. 97,447

Term of patent 3½ years

To all whom it may concern:

Be it known that I, Mario Frascino, a citizen of the United States of America, residing in New York city, county of New York and State of New York, have invented a new, original, and ornamental Design for a Coat, of which the following is a specification, reference being had to the accompanying drawing, forming part thereof, wherein,

I claim:

The ornamental design for a coat, substantially as shown.

MARIO FRASCINO.
